specification of Letters Patent. Patented Mar. 4, 1919.

Application filed May 19, 1917. Serial No. 169,621.

To all whom it may concern:

Be it known that I, WARD S. IRELAND, a citizen of the United States of America, a resident of the city of St. Louis, State of Missouri, have invented certain new and useful Improvements in Shorthand-Machines, of which the following is a full, clear, and exact description, reference being had to the accompanying drawings, forming a part of this specification.

My invention relates to improvements in shorthand machines, and more particularly to feeding devices adapted for use in shorthand machines. One of the most important considerations in the manufacture of machines of this kind is the elimination of clicking sounds, noisy hammer blows and the like. The feeding devices actuated by the universal bar should move silently and positively in response to the key movements, and my object is to accomplish both of these important results by means of a strong, simple and inexpensive combination of elements.

In the preferred form of the invention, the paper feeding device includes a clutch through which motion is transmitted from a universal bar. The drive member of the clutch is oscillated by the universal bar, and the driven clutch member rotates in one direction in response to the oscillatory movements of the drive member. When the oscillatory drive member turns in one direction, motion is positively transmitted to the driven clutch member, thereby accurately feeding the paper a fixed predetermined distance, and during its return stroke the drive member moves idly and silently, without transmitting motion to the driven clutch member.

Another object is to produce a simple and efficient means for preventing retrograde movement of the paper.

The paper is preferably fed by means of a pair of feed rolls, and to insure the desired positive or accurate feeding action, one of said rolls may be adjusted toward the other to firmly grip the paper. In the structure I have shown, the adjustable roll may be removed from the machine, and thereafter readily replaced in its operative position without changing the adjustment.

With the foregoing and other objects in

view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a longitudinal section of a short-hand machine constructed in accordance with my invention.

Fig. II is a transverse section on the line II—III, Fig. I.

Fig. III is a fragmentary side elevation partly in section, showing the key actuated universal bar and the paper feeding device driven thereby.

Fig. IV is a longitudinal section showing a paper feeding roll provided with clutches at its ends.

Fig. V is a section on line V—V, of Fig. IV, showing the retaining clutch.

Fig. VI is an enlarged section on line VI—VI, Fig. IV, showing the drive clutch.

Fig. VII is an enlarged fragmentary section showing the paper feeding rolls and the printing elements.

Fig. VIII is a detail view showing one of the adjustable bearings and the latch whereby one of the feed rolls is detachably secured thereto.

Fig. IX is a vertical section taken approximately on the line IX—IX, Fig. VIII.

Fig. X is a detail view of the other adjustable bearing.

Fig. XI is a vertical section taken approximately on a line XI—XI, Fig. X.

Fig. XII is a detail view of one of the adjustable bearings.

To illustrate the invention I have shown a short-hand machine provided with key levers 1 pivotally supported by a pivot rod 2, each key lever having an upturned printing hammer 3 at its rear end. Type characters 4 are formed on the bottom face of a type bar 5. 6 designates an inking ribbon passing between the printing hammers and the type characters. The strip of paper 7 unwinds from a supply roll 8 and travels downwardly to the transverse rod or roller 9, thence upwardly and over a paper feeding

roll 10, downwardly through an inclined guideway 11, and rearwardly to an opening at the rear of the machine.

The keys may be operated independently of each other, and several keys may be operated simultaneously to print a line of characters, as is well understood in this art. When a key is depressed its printing hammer 3 moves upwardly to force the paper 7 onto the inking ribbon 6, at the same time forcing the ribbon onto the type. 12 designates restoring springs which normally retain the key levers in the positions shown in the drawings.

15 The paper guide 11 extends downwardly and rearwardly from the paper feeding device to a point near the inking ribbon 6, where its front wall merges into a horizontal guide plate 13, the latter being provided 20 with an opening 14 through which the printing hammers are projected during the printing operations.

When a new roll of paper is mounted in the machine, the free end of the strip 7 may 25 be readily fed by hand through the inclined paper guide 11 to the horizontal guide plate 13 which deflects the paper rearwardly between the ribbon and printing hammers. The horizontal plate 13 supports the paper 30 near the printing hammers, and it co-operates with the inking ribbon 6 to form a guideway for the paper.

The paper feeding device includes the rotary feed roll 10 having a large gear wheel 35 15 which meshes with a smaller gear wheel 16, the latter being secured to a relatively small feed roll 17. The large feed roll 10 is driven through the medium of a universal bar and a clutch, as will be herein-after described, and motion is transmitted from the gear wheel 15 to the smaller gear wheel 16. The movements of the paper feeding rolls are thus synchronized, both rolls turning simultaneously to positively 45 feed the paper. The feed rolls differ in diameter but to obtain the desired feeding action, the pitch diameter of each gear wheel is equal to the diameter of the feed roll to which it is secured. Both feed rolls, therefore, turn at the same peripheral speed.

50 The feed roll 17 is detachably secured to the machine so that it may be readily removed to allow the operator to insert the paper by hand through the guide 11. Long journals 18, extending from the ends of the feed roll 17, are rotatably mounted in bearings 19 and 19', the bearing 19' having a circular opening in which one of the journals 18 is rotatably mounted (Fig. X), and 55 the bearing 19 being a substantially L-shaped device having an elongated opening 20 (Figs. VIII and XII) for the reception of the other journal. The elongated journal-receiving opening 20 is open at the 60 top of the bearing 19, as shown most clearly

in Fig. XII, so that one of the journals 18 may be readily inserted into said opening after the other journal 18 has been inserted into the bearing 19'. An arcuate face 21 (Fig. XII) at the bottom of the opening 20, forms a seat for one of the journals 18. When the journals 18 are properly fitted to the bearings 19 and 19', they are detachably secured by means of a latch 22 which engages one of the journals 18 to secure it in the bearing 19, as shown most clearly in Fig. VIII. The lower end of the latch 22 is pivotally connected to the bearing 19 by means of a pivot pin 23. 24 designates a spring connecting the latch 22 to the bearing 19, so as to yieldingly force said latch into engagement with the journal 18 which lies in the recess 20. This latch 22 has a hook shaped upper end (Fig. VIII) provided with a semi-circular face which engages the journal. A pin 24 (Figs. VIII and IX) passing through a large opening 25 in the latch 22, is secured to the bearing 19. When the latch 22 occupies the position shown by dotted lines in Fig. VIII, the feed roll 17 may be moved transversely of its axis to release one of the journals 18 from the bearing 19, and said feed roll may also be moved longitudinally of its axis to withdraw the other journal 18 from the circular opening in the bearing 19'. It will be observed that the feed roll 17 may be very easily detached from and replaced in its bearings 19 and 19'.

The bearings 19 and 19' are pivoted at 60 26 and 26' respectively, and they may be adjusted about the axes of their respective pivots to force the feed roll 17 toward the larger feed roll 10, the means for adjusting the bearings being shown most clearly in Figs. VII to XI inclusive. Each of the 65 bearings is provided with an elongated opening for the reception of a cam or eccentric 27 having a non-circular portion 28 to which a wrench may be applied for the purpose of turning the eccentric. Each eccentric 27 is rotatably mounted on a clamping screw 29. After the desired adjustment has been obtained the eccentrics are locked by tightening the clamping screws 29, thus securing the feed roll 17 in the operative position to which it has been adjusted. It will be observed that the feed roll 17 may be readily removed from the machine and afterward replaced in its operative position 70 without in any way changing the adjustment of the bearings.

The adjustable eccentric 27 associated with the bearing 19 (Fig. VIII) is closely fitted to the top and bottom walls of the opening in which it is mounted, so as to firmly secure the bearing 19 in the position to which it is adjusted. The other eccentric 27 (Fig. X) is not closely fitted to the top and bottom walls of the opening in which 75

it is mounted, the bearing 19' being seated on the top face of said eccentric, and the bottom wall of said opening being separated from the bottom face of said eccentric. The bearing 19' (Fig. X) is free to oscillate a slight distance about the axis of its pivot 26', and the eccentric 27 associated therewith serves as a stop for limiting the downward movement of said bearing. A spring 19^a (Figs. III and X) tends to retain the bearing 19' in engagement with the top face of eccentric 27. When both eccentrics 27 are properly adjusted, the desired firm contact will be obtained between the feed rolls 18 and the paper. The spring 19^a (Figs. III and X) tending to retain the bearing 19' in engagement with the top face of the adjacent eccentric 27, will yield to compensate for inaccuracies in the long journals 18, thus maintaining the paper in firm engagement with both feed rolls. The eccentric 27 (Fig. X) which limits the downward movement of the bearing 19' will prevent the small feed roll from sinking too deeply in the large feed roll. The long journals 18, mounted in the adjustable bearings 19, and 19' are formed by a long rod or shaft which passes through the small feed roll 17, and actual practice has shown that the rods obtainable for this purpose are not absolutely straight. As a consequence, the small feed roll 17 partakes of an irregular eccentric-like movement, and if the long journals 18 were mounted in fixed bearings 30 the small feed roll would not always firmly engage the paper. By mounting the long journals 18 in one fixed bearing 19 and one yielding bearing 19', as herein shown, the spring 19^a will allow the small feed roll to 40 yield and partake of an irregular eccentric movement, thereby compensating for the inaccuracies due to a slight bend in the long rod which forms the journals 18; at the same time constantly maintaining the necessary firm contact at the paper, and also preventing the small feed roll from sinking too deeply in the large feed roll.

I will now describe the universal bar and the clutch through which motion is transmitted from the key levers to the rotary feed roll 10. The universal bar 30, arranged over the key levers, is connected to the pivot rod 2 by means of a pair of approximately horizontal arms 31, the bar 30 being free to move 55 about the axis of the rod 2. An arm 32 extending upwardly from one of the arms 31 is notched at its upper end to receive a pin 33 projecting from an oscillatory clutch member A (Figs. III, IV and VI). The universal bar, or universal frame is thus loosely interlocked with the oscillatory clutch member. This clutch member is mounted on the shaft 34 to which the feed roll 10 is secured. A rotary driven clutch member B, fixed to the feed roll 10 and shaft

34 is provided with an annular flange 36 forming a pocket for the oscillatory drive member A. The peripheral face of the oscillatory drive member A is recessed to form wedge-shaped spaces 37 between the clutch members A and B, as shown in Fig. VI. Transmission members 38, preferably in the form of small rollers, are mounted in the wedge-shaped spaces between the clutch members A and B. The driven clutch member B has a smooth circular face forming a seat for the transmission members 38, and the oscillatory member A is provided with angular seats 39 to which said transmission members are fitted. Spring pressed plungers 40 force the transmission members 38 onto their seats. The springs 41 arranged behind the plungers 40 tend to force the transmission members 38 toward the restricted points in the wedge shaped spaces 37. When the oscillatory drive member A turns in the direction indicated by the arrow in Fig. VI, the transmission rollers 38 are placed under compression and firmly gripped between the angular seats 39 on the drive member and the circular inner face of the driven member B. In other words, the transmission rollers 38 are frictionally gripped in the wedge shaped spaces 37 to provide for the transmission of movement to the roller rotary driven member B. The spring pressed plungers 40 constantly maintain the transmission rollers 38 in engagement with both of the clutch members A and B, so that the driven member B will respond instantly to the operative movement of the drive member A. The movement of the driven member is absolutely positive, the transmission rollers 38 being constantly forced into engagement with both clutch members, and when the drive member A turns in the direction indicated by the arrow (Fig. VI) all of the transmission members are more firmly wedged between the clutch members.

During the return stroke of the drive member A, it turns in a direction opposite to that indicated by the arrow in Fig. VI, without transmitting movement to the drive member B. At this time, the transmission rollers 38 tend to move into relatively wide portions of the wedge-shaped pockets or spaces 37, and then move freely on the smooth circular inner face of the member B. It will be observed that the various clutch members perform their functions silently, without causing clicking sounds, noisy hammer blows or any other noise.

The universal bar is oscillated during each key operation, and it transmits an oscillatory movement to the drive clutch member A, thereby causing the rotary driven clutch member B to actuate the paper feeding rolls. The universal bar 30 is moved upwardly by the key levers and restored by a spring 43

(Figs. I and VII). The movements of the key levers are limited by the type 4, and the universal bar, therefore, moves a fixed predetermined distance during each key operation. Since the friction clutch responds instantly to the operative strokes of the universal bar, it will be apparent that the paper is fed a fixed predetermined distance during each key operation.

- 10 To prevent retrograde movement, I preferably utilize a retaining clutch constructed similar to driving clutch. This retaining clutch comprises a rotary clutch member B' (Figs. II, IV and V) fixed to the feed roll 10 and also fixed to the shaft 34, a stationary clutch member A' fixed to a side frame 45 by means of a pin 46, and spring pressed retaining rollers 38' mounted in wedge-shaped spaces between the stationary clutch member A' and a flange 36' on the rotary clutch member. The springs constantly maintain the retaining rollers 38' in engagement with both clutch members A' and B', and said rollers yield freely to allow the 25 rotary clutch member and feed roll 10 to turn in the direction indicated by the arrow in Fig. V. If an effort is made to reverse the direction of movement, the retaining rollers 38' tending to move toward the points 30 of the wedge-shaped spaces will be placed under compression and firmly gripped between the clutch members, so as to positively prevent such retrograde movement. While I have shown three retaining rollers 38' and 35 three transmission rollers 38, it will be observed that any desired number of these elements may be utilized in the clutches.

- The printing elements grip the paper immediately before the paper feeding operation is completed, and if the paper was positively pulled while gripped by the printing elements, it is apparent that the printed matter would be blurred or the paper would be unduly strained. To overcome this I pull 40 the paper from the supply roll and push it to the printing elements. The paper feeding device is arranged between the supply roll 8 and the printing elements. When the printing elements grip the paper, the printing keys continue in motion to obtain the required pressure at the type, and during this continued movement the paper feeding device is actuated by the keys, but the paper is merely pushed and permitted to bend 45 slightly in the guideway 11, without blurring the printed matter and without tearing or otherwise straining the paper.

I claim:—

1. In a typewriting machine, the combination of a key actuated universal bar, and feeding device including a friction clutch through which motion is transmitted from said universal bar, said friction clutch comprising a drive member loosely interlocked 50 with and operated by the universal bar, a

rotary driven member adjacent to said drive member, a wedge-shaped space being formed between said drive member and driven member, and a transmission member seated in said wedge-shaped space, said transmission 70 member being wedged between and firmly gripped by said drive member and driven member when the drive member turns in one direction, and the drive member being free to turn in the opposite direction without 75 transmitting movement to said driven member.

2. A typewriting machine having key levers, a universal bar operated by said key levers, and a feeding device including a 80 friction clutch through which motion is transmitted from said universal bar, said friction clutch comprising a rotary driven clutch member, an oscillatory drive member movable about the axis of said rotary 85 driven member, said oscillatory drive member having a projection and the universal bar being provided with an operating arm loosely interlocked with said projection, and a transmission member arranged to be frictionally gripped by said drive member and driven member in response to the operative movements of said drive member, said transmission member being free to yield without transmitting movement when the drive 90 member turns in one direction.

3. A shorthand machine having key actuated paper feeding rolls, bearings in which one of said rolls is rotatably mounted, pivotal supports for said bearings, and 100 means for adjusting said bearings about their pivots to force the last mentioned roll toward the other roll, said means including eccentrics fitted to said bearings, and a spring coöperating with one of said bearings to yieldingly retain it in engagement with its eccentric, the other bearing being engaged with diametrically opposite faces of its eccentric. 105

4. A shorthand machine having key actuated paper feeding rolls, bearings in which one of said rolls is rotatably mounted, pivotal supports for said bearings, means for adjusting said bearings about their pivots to force the last mentioned roll toward the 110 other roll, said means including eccentrics fitted to said bearings, and a spring coöperating with one of said bearings to yieldingly retain it in engagement with its eccentric, the other bearing being engaged with 115 diametrically opposite faces of its eccentric, and clamp screws for retaining said eccentrics in the positions to which they are adjusted.

5. A typewriting machine having key actuated paper feeding rolls, bearings supporting one of said rolls, means for adjusting said bearings to force the last mentioned roll toward the other roll, and a latch device detachably securing the adjustable roll to 125 130

- 5 said bearings, said latch device being carried by one of said adjustable bearings to allow the adjustable roll to be readily removed and replaced without changing the adjustment of the bearings.
- 10 6. A typewriting machine having key actuated paper feeding rolls, gear wheels secured to the respective rolls, said gear wheels being in mesh with each other so as to synchronize the movement of the rolls, a fixed bearing in which one end of one of the rolls is mounted, and a yieldable bearing in which the opposite end of the last mentioned roll is mounted.
- 15 7. A typewriting machine having key actuated paper feeding rolls, gear wheels secured to the respective rolls, said gear wheels being in mesh with each other so as to synchronize the movement of the rolls, a fixed bearing in which one end of one of the rolls is mounted, and a yieldable bearing in which the opposite end of the last mentioned roll is mounted, said fixed bearing being adjacent to said gear wheels.
- 20 8. A shorthand machine having a paper feeding device, a paper guide extending downwardly from said paper feeding device, a rearwardly extending paper guide forming a continuation of the first mentioned
- 25 paper guide, and opposing printing elements arranged to engage the paper after it reaches said rearwardly extending paper guide.
- 30 9. A shorthand machine having printing elements including an inking ribbon and printing hammers below said ribbon, a paper feeding device for feeding a strip of paper between said ribbon and printing hammers, and a guide plate for the paper arranged below said ribbon, said guide plate having an opening through which the printing hammers can be projected to engage the paper and said guide plate being arranged opposite to and separated from the ribbon so as to coöperate therewith in forming a guide for the paper.
- 35 10. A shorthand machine having a paper feeding device including two rotary feed rolls coöoperating with each other to feed the paper, a fixed bearing for one end of one of said rolls, a yieldable bearing for the other end of the last mentioned roll, and a spring associated with said yieldable bearing to force the last mentioned roll toward the other roll, thereby maintaining both rolls in firm engagement with the paper.

WARD S. IRELAND.
